UNITED STATES PATENT OFFICE.

CHARLES R. GREUTER, OF WILKES-BARRE, PENNSYLVANIA.

CARBURETER.

No. 888,487.

Specification of Letters Patent.

Patented May 26, 1908.

Application filed June 5, 1906. Serial No. 320,322.

To all whom it may concern:

Be it known that I, CHARLES R. GREUTER, a citizen of the United States, and resident of Wilkes-Barre, in the county of Luzerne and State of Pennsylvania, have invented certain new and useful Improvements in Carbureters, of which the following is a specification.

This invention relates to carbureter appliances of the type possessing special utility in connection with high power motors such as are employed on motor vehicles.

To this end the invention contemplates a simple, practical and efficient construction of carbureter embodying means for securing the proper amount and mixture of air and hydro-carbon under the varying load conditions imposed upon the motor.

The essential features of the invention are necessarily susceptible to structural change without departing from the scope thereof, but a preferred embodiment thereof is shown in the accompanying drawings, in which:

Figure 1 is a vertical longitudinal sectional view of the carbureter. Fig. 2 is a vertical transverse sectional view on the line 2—2 of Fig. 1.

Like references designate corresponding parts in the several figures of the drawings.

The invention embodies in its general organization a main mixer casing designated in its entirety by the numeral 1 and consisting of a suitably shaped casing adapted for the purposes of the invention. The mixer casing 1 is constructed with what may be properly designated the upper mixing chamber 2 and a lower air chamber 3 separated by a valve seat opening 4 adapted to be covered and uncovered by an air valve 5, which under normal conditions constitutes a separating diaphragm between the chambers 2 and 3, while at the same time under other conditions the said valve acts in the capacity of a supplemental suction air valve for admitting and regulating an additional supply of air to the chamber 3 from the chamber 2. The valve 5 is formed with the central opening 6 and is provided with a pendent guiding sleeve 7 at the lower end of which is formed an abutment collar 8 the purposes of which will be presently explained.

Considering in the first instance the air valve 5 as a separating diaphragm, the same receives through the opening 6 and sleeve thereof a centrally arranged and upright mixing tube 9 having at its upper end a flaring discharge mouth 10 and provided with

a flanged lower end 11 extending through the bottom of the air chamber 3 and secured on the outer side thereof, as plainly shown in Figs. 1 and 2 of the drawings.

At a point within the casing 1 the mixing tube 9 is provided with an air port 12 in open communication with the air chamber 3 and the pipe extension 13 of said chamber, which extension constitutes an air inlet tube for the mixture casing and is in open communication with the outer atmosphere. The lower flanged end 11 of the mixing tube 9 outside of the casing 1 is seated on the flanged rest base 14 formed on the upper side, and contiguous to one end of a hydro-carbon supply pipe 15 which is designed to receive the hydro-carbon or liquid fuel from a suitable fuel reservoir 16 connected therewith. The rest base 14 of the fuel supply pipe 15 also has supported thereon inside of the tube 9 a fuel feeding tube 17 having at its lower extremity an inlet nipple 18 constituting a valve seat for a needle feed controlling valve 19 mounted in a screw threaded boxing 20 and is provided with a threaded fitting 21 and a hand wheel 22 for manual control, said wheel having extended therefrom suitably controlled operating connections 39—40. The fuel feeding pipe 17 is arranged concentrically and longitudinally of the mixing tube 9 for the greater portion of the length of the latter.

The air valve 5 has associated therewith a pressure lever 22^a pivotally mounted between its ends as at 23, within the air inlet tube 13, and having a forked engaging end 24 taking over the valve sleeve 7 and bearing on the collar 8 thereof. The opposite end of the pressure lever 22^a has connected therewith a tension link 25 extending through the tube 13 and receiving the pressure of the tension of an exterior pressure spring 26. An adjustable regulating stop 27 mounted in one side of the air inlet 13 and arranged in the path of the pressure lever 22^a regulates the play of such lever, and hence regulates the degree of opening of the valve 5.

The upper mixing chamber 2 is surmounted by a valve casing 28 in communication with the chamber 2 and formed with a cylindrical valve chamber 29 accommodating therein the hollow cylindrical throttle valve 30 provided with a bottom inlet port 31 for the mixture and with a top narrow auxiliary air inlet opening 32 in alignment with port 31 and adapted to register with a supplemental

air inlet port 33 formed in the top of the valve chamber 29 and adapted to be covered and uncovered more or less by a slide valve 34. This slide valve 34 is designed to have 5 suitably controlled operating connections 39a—41 which are utilized to move the valve when the conditions of the load require the admission of additional air into the mixture at the point of discharge through the throttle 10 valve 30. The throttle valve 30 is provided at one end with a rocking valve stem 36 extending through the casing 28 and is provided with a controlling connection 37 so that the outlet of the mixture from the chamber 2 may be 15 controlled. When the throttle valve 30 is nearly closed the air suction in the chamber 2 is very much reduced, and is not sufficient to raise the valve 5 from its seat. When the throttle is wide open, the suction in the chamber 20 2 is very much increased, and the valve 5 is lifted to the highest point, permitting a considerable quantity of air to pass into the chamber 2 between the valve 5 and its seat. The diameter of the chamber 2 being 25 reduced above the top of the mixing tube 9 causes the air which rushes into the chamber 2 between the valve 5 and its seat to be deflected and intimately mixed and mingled with the hydro-carbon laden air which enters the chamber through the mixing tube 9. As the throttle is closed the tension of the 30 spring 26 gradually returns the valve 5 towards its seat.

I have also shown in Fig. 1 a deflector 38 35 mounted immediately above the top of the mixing tube 9, the purpose of which is to deflect the hydro-carbon laden air which passes up through the top of the mixing tube 9 and causes it to mingle with the air which 40 enters the mixing chamber between the valve 5 and its seat when the valve is raised.

I claim:

1. A carbureter comprising a mixer casing

having an air chamber and a mixing chamber, a mixing tube extending through the air 45 chamber into the mixing chamber and provided with an air port opening into the former, fuel feeding means discharging into the mixing tube, an air valve arranged to constitute a diaphragm between the two chambers 50 and provided with a sleeve member slidably mounted on the mixing tube, a spring held lever engaging the air valve and normally holding the same closed, and an adjustable regulator for said lever.

2. A carbureter comprising a mixer casing having an air chamber and a mixing chamber, a mixing tube in communication with the air chamber and projecting into the mixing chamber, liquid fuel supply means 60 discharging into the mixing tube and having a feed controlling valve therefor, an automatic air valve separating the two chambers, a discharge valve casing in communication with the mixing chamber and provided 65 with an auxiliary air inlet port, and a suitably operated throttle valve mounted in said valve casing and having an air inlet opening and also an outlet port for the mixture.

3. A carbureter comprising a mixer casing 70 having an air chamber and a mixing chamber, a mixing tube extended through and in communication with the air chamber, a supplemental air valve arranged to constitute a diaphragm between the two chambers and 75 provided with a sleeve that is slidably mounted on the mixing tube, and a pivotally mounted lever having an engagement with the said valve sleeve.

Signed at Wilkes-Barre in the county of 80 Luzerne and State of Pennsylvania this 10th day of May A. D. 1906.

CHAS. R. GREUTER.
